UNITED STATES PATENT OFFICE

WILLIAM J. REGAN, OF WILKINSBURG, AND ENOCH GEORGE, JR., OF PITTSBURGH, PENNSYLVANIA, ASSIGNORS TO THE McCONWAY & TORLEY COMPANY, OF PITTSBURGH, PENNSYLVANIA, A CORPORATION OF PENNSYLVANIA

RAILWAY DRAFT APPLIANCE

Application filed February 27, 1928. Serial No. 257,321.

This invention relates to draft appliances for railway cars and particularly to means for flexibly connecting the rear end of a coupler shank to a draft yoke.

5 The principal object of the invention is to provide a construction permitting the standard American Railway Association design of coupler to swing laterally with respect to the yoke and to provide a form of cooperating yoke for which a standard American Railway Association yoke may be substituted when making renewals or in an emergency.

10 The primary feature of the invention, generally stated, consists in interposing between the stem of a car coupler and a draft yoke, a member which is connected to the coupler by a key and is connected to the yoke by vertically alined pivot pins whose axes are coincident and disposed in advance of the rear end 15 of the coupler stem, the said pins being related to the parts which they connect in such manner as to be in double shear.

A further feature of the invention consists in interposing between the yoke and coupler 25 a member which is pivotally movable with respect to the yoke, said member being formed with vertically spaced openings for respectively receiving the arms of the yoke and the stem of the coupler, the coupler stem being 30 interposed between the yoke arms in overlapped relation thereto, means being provided for pivotally connecting said member to the yoke, and a key being employed for connecting said member to the coupler.

35 In the drawing illustrating preferred embodiments of the invention:

Figure 1 is a view, partly in plan and partly in horizontal section, of a construction embodying the invention, portions of the coupler, yoke and the transverse connecting key being broken away.

Figure 2 is a view, partly in vertical section and partly in elevation, of the construction shown in Figure 1.

40 Figure 3 is a view corresponding to Figure 1 but illustrating a modified form of the invention in which the arms of the yoke are connected near their forward ends by an integral tie.

45 Figure 4 is a vertical central section of the

structure shown in Figure 3, the car coupler and the pivot pins being in elevation.

Figure 5 is a view corresponding to Figure 1, but illustrating a modified embodiment of the invention in which an independent bearing block or seat is provided for cooperating with the rear end of the coupler stem in buffering.

55 Figure 6 is a vertical central section of the device shown in Figure 5, the car coupler and pivot pins being in elevation.

60 In the construction illustrated in Figures 1 and 2, the stem 1 of the car coupler is of the standard American Railway Association design. It is formed near its rear end with a transverse slot 2 for receiving the usual key 3. The yoke 4, which may be of the conventional U-shape, is fashioned at the forward ends of its spaced arms 5 with pivot lugs 6 having vertically alined perforations 7 for receiving corresponding pivot pins 8. The arms of the yoke overlap the rear end of the coupler stem so that the axes of the pivot pins 8 are disposed in advance of the rear end of the coupler and the cylindrical bodies of the pins overlap the coupler key 3 above and below the latter.

65 Interposed between the yoke and the stem 1 of the car coupler and embracing the latter is a yoke-head or frame member 9 having an opening 10 for receiving the rear end of the coupler stem. It is also formed with open ended slots 11 for respectively receiving the arms 5 of the yoke, as well as being formed with transversely alined elongated slots 12 for receiving the key 3. Each of the slots 11 is spaced away from the adjacent side of the coupler stem 1 to permit the provision in the member 9, immediately above and below the coupler shank, of horizontal tie walls 13 which are parallel to the outer walls 14 of the slots 11. The walls 13 and 14 have suitable openings for receiving the respective headed pivot pins 8, thereby enabling the latter to be in double shear when the yoke 4 is pulled forward in draft. Flexibly connecting the member 9 to the yoke 4 enables the sides of the member 9 in which the key slots 12 are formed to be spaced apart an amount just sufficient to allow the coupler 70 75 80 85 90 95 100

shank 1 to be received between them, thus reducing the bending strain in the draft key 3 below the stress that is developed in this key when it is used with the present American 5 Railway Association yokes.

In assembling this device the forward ends 6 of the yoke are inserted in the corresponding openings 11 of the yoke-head member 9 and the pivot pins 8 are then inserted in their 10 proper openings to effect the connection of these two parts, the headed end of each pivot pin being uppermost. The draft gear (not shown) is then inserted between the yoke arms and the parts thus assembled are raised 15 into position and mounted on the car as a unit in the usual way. The rear end of the stem of the coupler 1 is then inserted in the opening 10 of the member 9 and the transverse key is thereafter passed through the slots 2 20 and 12.

No cotters or other means are required to hold the pivot pins 8 in place and the upper pivot pin will occupy a position just below the bottom of the car floor plates, while the 25 underside of the coupler stem 1 prevents the lower pivot pin from jumping or creeping upward.

The embodiment of the invention illustrated in Figures 3 and 4 is generally the 30 same as that disclosed in Figures 1 and 2, except that the rear end of the coupler shank 15 is cylindrically curved, as at 16, concentric with the axes of the pivot pins 8, the arms 5 of the draft yoke being integrally united 35 just to the rear of their pivot lugs 6 by a vertical wall 17, whose forward face 18 is curved to correspond to the curved rear end of the coupler shank. The forward curved surface 18 of the wall 17 affords a large bearing area 40 for the end of the coupler shank in buffering in any position the coupler may occupy, while the rear face 19 of this wall provides an extended bearing area for the forward follower or draft gear when buffering. The rear 45 edges 20 of the horizontal tie walls 13 of the yoke-head member are, as shown, suitably formed to afford ample clearance for the vertical tie wall 17 of the yoke. The remaining features of construction of this embodiment 50 of the invention correspond in form and function to similar details shown in Figures 1 and 2 and heretofore described, and accordingly the corresponding features have been identified by the same reference 55 numerals.

Figures 5 and 6 illustrate a construction in which the rear end of the coupler shank 21 is cylindrically curved, as at 22, concentric with the pivot pins 8 to cooperate with a 60 bearing block 23 having a correspondingly curved seat 24, the block being independent of the yoke and being positioned at the rear end of the coupler stem between the interior walls 13 of the yoke-head member 9. Other 65 features of construction are the same as those

heretofore described and have therefore been indicated by corresponding reference numerals. The design of the coupler shank 21, bearing block 23 and yoke 4, are such that a standard American Railway Association coupler may be substituted for the coupler and bearing block shown.

The manner of assembling the devices shown in Figures 3 to 5 inclusive is substantially the same as that heretofore described in respect to the construction shown in Figures 1 and 2, as will be readily understood.

We claim:

1. In a railway draft appliance, the combination with a yoke having a plurality of spaced arms which are integrally united adjacent their forward ends by a substantially vertical wall, a car coupler having a stem interposed between said arms and adapted to contact said vertical wall in buffering, a member operatively associated with the yoke and coupler for permitting pivotal movement of the latter with respect to the yoke, said member having a plurality of slots for respectively receiving the arms of the yoke, means for pivotally connecting the yoke to said member, and a key for connecting the latter to the coupler, the rear end of the coupler stem and said vertical wall having cooperating concentrically curved bearing faces.

2. In a railway draft appliance, the combination with a yoke having a plurality of spaced arms, of a car coupler having a stem extending between said arms, a member operatively associated with the yoke and coupler for permitting pivotal movement of the latter with respect to the yoke, said member having a plurality of slots for receiving the arms of the yoke, means for pivotally connecting the yoke to said member, a key for connecting the latter to the coupler, and means at the rear of the coupler stem adapted to engage the forward follower of a draft rigging, said last named means and the end of the coupler stem having cooperating curved bearing faces.

In testimony whereof we affix our signatures.
